UNITED STATES PATENT OFFICE.

DENNIS C. WILCOX, OF WEST MERIDEN, CONNECTICUT, ASSIGNOR TO THE MERIDEN BRITANNIA COMPANY, OF SAME PLACE.

DESIGN FOR TEA-SETS.

Specification forming part of Design No. 7,376, dated April 14, 1874; application filed March 18, 1874.
 [Term of Patent 7 years.]

To all whom it may concern:

Be it known that I, DENNIS C. WILCOX, of West Meriden, in the county of New Haven and State of Connecticut, have invented a new Design for Tea-Set; and I do hereby declare the following, when taken in connection with the accompanying illustration and the letters of reference marked thereon, to be a full, clear, and exact description of the same, and which said illustration constitutes part of this specification, and represents a perspective view of the several pieces which constitute the set.

This invention relates to a design for tea-set; and consists in the peculiar form in outline, as shown in the accompanying illustration, as a set or individual pieces.

The several pieces possess the same characteristic outlines. From a vertical or nearly vertical base the body rises, expanding in a convex form to a central raised band, running around the body. From this band the body is drawn back, in corresponding convex form

to the body below the band, to the neck, which is similar to the base. On those articles which require it—as the pots and sugar—a cover is applied, and to each, according to its use, a spout or handle, or both, is applied, as shown.

I do not wish to be understood as confining my design to the combined articles going to make up a set, but collectively or individually, as may be demanded.

I claim as my invention—

The design for tea-set, consisting of a base, from which the body rises, expanding in a convex form to a central raised band, thence contracting in a similar convex form to the neck, as shown in the accompanying illustration and herein described.

DENNIS C. WILCOX.
